UNITED STATES PATENT OFFICE.

ROY W. PACE AND JACK E. WILLETT, OF LOS ANGELES, CALIFORNIA.

BOX-CAR-DOOR OPENING AND CLOSING DEVICE AND FASTENER.

Application filed June 21, 1923. Serial No. 646,816.

To all whom it may concern:

Be it known that we, ROY W. PACE and JACK E. WILLETT, citizens of the United States, residing at Los Angeles, in the county of Los Angeles and State of California, have invented new and useful Improvements in Box-Car-Door Opening and Closing Devices and Fasteners, of which the following is a specification.

10 Our present invention is a box car door opening and closing device and fastener, and it is an especial object of this invention to provide convenient and effective means for opening or closing or securing any heavy 15 door which is adapted to move laterally in the customary manner of sliding doors, such as are commonly provided with rollers, ordinarily secured at or near the top thereof and adapted to engage a fixed track.

20 It being well known that the doors of box cars, and the like, are liable to "stick" in such manner that it is often difficult or impossible to open or close the same without the use of tools, or without damage to such 25 doors or to adjacent parts, it is an object of this invention to provide mechanical means, preferably comprising a crank on the door, and a rack on the car, this rack being adapted to be engaged by a pinion with which 30 said crank is operatively connected, for moving said door in either direction; and, in a preferred embodiment of our invention, we prefer to make the crank relatively movable in such manner as to permit its use 35 also as a hasp, to cooperate with the padlock, or the like, in retaining said door in its closed position; and our door may be releasably retained in any adjusted position.

Broadly, it is an object of this invention 40 to provide a sliding door, or the like, with means comprising a hand operated motor thereon, for moving the same, at will, in either direction and for locking the same in an adjusted position.

45 Other objects of our invention will appear from the following description of a preferred embodiment thereof and from the appended claims, taken in connection with the accompanying drawings, in which:

50 Figure 1 is a side elevation of a door and door opening in connection with which our

invention is employed, parts being broken away to show a fixed track integral with a supporting rail for said door.

Figure 2 is a similar view, showing the 55 essential working parts of our device upon an enlarged scale, additional parts being broken away or shown in section.

Fig. 3 is a vertical section on line 3—3 of Figure 2.

Fig. 4 is a side elevation showing how the operating handle of our device may be used as a locking means.

Fig. 5 may be regarded as a section on line 5—5 of Figure 4.

Referring in detail to the parts of that specific embodiment of our invention which we have chosen for purposes of illustration, 1 may be regarded as a body of a box car, or the like, provided with a door 2, adapted 70 to close an opening 3, and supported by usual means such as rollers 4, mounted in brackets 5, and engaging a track 6, which may constitute the up-turned edge of a plate 7, secured to the side of a car 1, or 75 the like, by means such as screws 8. The rail or track 6 and the associated supporting elements mentioned may advantageously be protected by a housing 9, of sheet metal or 80 the like, and this housing may advantageously be extended to include a vertical housing element 10 and 11, which may be extended to and united with a bottom housing element 12, which may also serve as a 85 guide for the bottom of the door 2, all the mentioned housings being adapted to cooperate in an exclusion of the weather and a prevention of tampering.

Coming now more particularly to our novel door operating means, at or near the 90 point where a handle or a lock is commonly secured to a door, we prefer to secure, adjacent the "lock" edge 13 of our door, a guard plate 14, whose lateral faces may be cut away to provide for bearing plates 15 and 15', both said guard plate 14 and said bearing plates 15, 15' being secured to the door 2 by means such as the screws or bolts 16, 17, and the said bearing plates being adapted to support the ends of a short horizontal shaft 18, to which a worm gear 19 is shown as secured by a set screw 20, the

said worm gear being adapted to cooperate with a worm wheel 21, shown as revolving upon a substantially vertical shaft 22; this shaft being secured and supported by means 5 such as a protecting and bearing sleeve 23, shown as secured to the actual edge of the door 2, all of the mentioned parts being protected by the guard plate 14 and the bearing plates 15, 15'.

10 In order to utilize the rotative movement of the shaft 22 in imparting movement to the door 2, any suitable means may be provided, but we prefer to employ, for this purpose, rack engaging means such as a 15 pinion 24, suitably secured to the shaft 22, it being ordinarily sufficient to employ such a pinion at the upper end only of said shaft, and to adapt the same to cooperate with the rack fixed upon the body of the car, or the 20 like, in connection with which our door operating means may be employed. For the purpose referred to, we find it advantageous to employ a rack adjacent to or integral with the rail 6, the rack 25 being shown as 25 consisting, essentially, of a suitable row of perforations in the re-curved edge of the plate 7, with which the rail 6 may be integral.

Although any suitable means might be 30 employed to impart movement to the worm 19, and thereby to the door 2, we have preferred to employ, for this purpose, a crank 26, co-axial with the short horizontal shaft 18; and, in order to adapt the said crank to 35 serve also as a hasp, cooperating with a loop or staple 27, secured to a fixed part such as the housing element 11, we may provide an aperture 28 in such crank, in order to permit the use of a padlock 29, or the like, in 40 securing the door 2 in its adjusted position, the crank 26 being shown as bent at 29 and 30, and as hingedly connected by a pivot 31 to a plate 32, adapted to rotate with or upon the shaft 18.

45 It being obvious that the door 2 must be completely closed before it can be locked in the manner just referred to, we find it important to provide means permitting the crank 26 to be rotated either with or independently of the short shaft 18, and for this 50 purpose we propose the use of a disc 33, shown as keyed to the said shaft and as provided with lugs 34, adapted to be engaged at will by the crank 26; the construction 55 being such that when the disc 33, and parts connected therewith, have been rotated sufficiently to close the door 2, the crank 26 may then be swung upon the hinge pin 31, out of contact with the lugs 34, and the 60 plate 32 may then be rotated into the position shown in Figure 5, enabling the door to be locked in the manner there shown.

65 In connection with the foregoing, it will be understood that any usual or preferred type of supporting track and rollers may

be used; and also that, although the worm 19 is adapted to impart motion to the worm wheel 21, the pitch relationships between the teeth of these last mentioned elements is such that the parts referred to constitute 70 an irreversible transmission, it being practically impossible, by pressure or blows, to move a door 2, provided with our operating means, from any adjusted position, so long as the worm 19 and the worm wheel 21 remain in mesh. 75

From the point of view just indicated, our described organization may be referred to as comprising means for placing a car door in any desired position, and it may also be referred to as constituting or comprising means for locking a car door open at any desired point or to any desired extent. It being frequently desirable to leave a car door slightly open, for purposes of 80 ventilation, whether or not human beings are traveling therein (as may be necessary in the shipment of live stock, or the like), we deem it advantageous to provide means, accessible from the inside of a car, to permit a disengagement of the worm wheel 21 from the worm 19; and, for this purpose, we may employ means such as a handle 36, secured to a short shaft 37, it being ordinarily unnecessary to duplicate this handle 85 on the outside of a car door, by which a curved arm 38, secured to said short shaft, may be employed to cam the worm wheel 21 out of engagement with the worm 19, the shaft 22 being, in this case, provided with 90 a squared collar or section 39, upon which the worm wheel 39 may slide, although incapable of rotation independently of said shaft. 95

100 It will be obvious that, although cars may be originally provided, during the course of their construction, with doors and door operating means of the character herein described, our doors and associated parts, including the frame elements 10 and 11, which may be screwed or bolted or otherwise secured to any suitable opening, may be manufactured in standard sizes, and may be readily applied to existing cars, replacing the doors now in use thereon. 105

110 It is believed that the general construction and mode of operation of our novel door operating and fastening device will be fully understood from the foregoing description, although it will be understood that parts referred to may be duplicated or positioned as required by the character or construction of a particular door or doors in connection with which our invention is 115 to be employed.

120 Although we have herein described but one complete embodiment of our invention, it will be understood that various features thereof might be independently employed, and also that various modifications might 125 130

be made therein without departure from the spirit and scope of our invention, as the same is indicated above and in the following claims.

5. What we claim is:

1. A sliding door construction, comprising in combination a plate having the main portion adapted to be secured to a structure, an upturned edge spaced from the

10 main portion, having apertures therethrough forming a rack, the upper surfaces of the edge forming a track, a door having wheels operating on the track, a vertical shaft having a pinion engaging the rack, a worm

15 wheel mounted on the vertical shaft, a work gear mounted on a horizontal shaft transverse of the door and a crank loosely mounted on the end of the horizontal shaft and means to operatively connect the crank to

20 the horizontal shaft to thereby operate the door.

2. A sliding door construction as claimed in claim 1, in which a plate is rotatable on the end of the horizontal shaft, the crank being hinged thereto and a disc mounted on the horizontal shaft surrounding the plate, and means to interengage the crank and the disc whereby the crank rotates the disc and hence the horizontal shaft.

3. A sliding door construction having in combination a rail, a rack formed integral therewith, wheels running on the rack, a door connected to the wheels, a casing forming part of the door structure, a vertical shaft mounted therein having a pinion at the upper end and a gear at the lower end, a horizontal shaft extending across the casing having a driving gear to mesh with the gear on the vertical shaft, and a crank to operate the horizontal shaft, said crank being loosely mounted on the horizontal shaft and having operative means to form a rigid connection therewith.

4. A sliding door construction as claimed in claim 3 having in addition means within the said casing to disengage the gears.

5. A sliding door construction comprising a rail, a rack formed integral with the rail, wheels running on the rack, a door connected to the wheels, a casing on one edge of

the door, a vertical shaft mounted in the casing with a pinion at the upper end and a worm gear at the lower end thereof, a horizontal shaft having bearings in the opposite sides of the casing, a worm gear thereon to engage with the worm gear first mentioned, a crank to operate the horizontal shaft, and means to disengage the worm gears.

6. A sliding door construction as claimed in claim 5 in which the means to disengage the gears comprises a cam bearing against the gear on the vertical shaft, and a handle to operate the cam.

7. A sliding door construction comprising a rail, a rack comprising a series of apertures formed integral with the rail, wheels running on the rail, a door connected to the wheels, a casing at the front edge of the door, a vertical shaft mounted in the casing having a pinion at the upper end and a worm gear at the lower end, a horizontal shaft through the casing having a driving worm gear to engage with the worm gear first mentioned, a crank to operate the horizontal shaft, a cam mounted in the casing engaging the gear on the vertical shaft, and a spring engaging the gear on the side opposite the cam.

8. A sliding door construction as claimed in claim 7 in which a handle extending through the casing engages the cam to disengage the gear on the vertical shaft from the gear on the horizontal shaft.

9. A sliding door construction comprising a rail, a rack formed integral with the rail, wheels running on the rack, a door connected to the wheels, a shaft mounted in the front edge of the door, a pinion upon the shaft meshing with the rack, a counter-shaft mounted in the car door near its edge, a worm and gear connecting the counter-shaft to the first shaft, and a crank hingedly connected to the counter-shaft and serving as a handle for rotating the counter-shaft to move the door, said crank serving as a hasp for use in locking the door.

In testimony whereof we have signed our names to this specification.

ROY W. PACE.

JACK E. WILLETT.
